United States Patent Office.

ELISHA MORGAN, OF SPRINGFIELD, MASSACHUSETTS.

Design No. 2,688, dated June 25, 1867.

DESIGN FOR AN ENVELOPE.

The Schedule referred to in these Letters Patent and making part of the same.

TO ALL WHOM IT MAY CONCERN:

Be it known that I, ELISHA MORGAN, of Springfield, in the county of Hampden, and State of Massachusetts, have invented a new and useful Design for Envelopes; and I do hereby declare that the following is a full, clear, and exact description thereof, which will enable others skilled in the art to understand the same, reference being had to the drawings, forming part of this specification.

The drawings are a back view of this invention.

This invention relates to an ornamental design for envelopes, whereby said envelope attains a novel and elegant appearance, which distinguishes the same from all envelopes heretofore made and known to me.

Figure 1. A represents the top side flap, which extends from the corners *a a*, with inclined sides, to *b b*; thence by inclined sides to *c c*; thence by curved sides to *d d*; thence from the points *d d* to *e*. That portion of the flap A from the points *d d* to the point *e* is designed for adhesive gumming, for sealing the envelope, the application of the gum being restricted between the points *d d*. B represents the bottom side flap, of the same shape as the flap A. C C represent the end flaps, folded under the bottom side flap B, the ends of the same meeting the point of the bottom side flap B at *f*, forming the pocket D, of a similar shape as the top side flap A, covering the same.

Figure 2 represents the envelope, described and shown in fig. 1, with the top side flap folded down, covering the pocket D.

What I claim as new, and desire to secure by Letters Patent, is—
The design for an envelope as shown and described.

The above specification of my invention signed by me this twenty-fourth day of May, A. D. 1867.
